ASH TRAY

Alfred R. Albert, Chicago, Ill.

Application July 26, 1951, Serial No. 16,041

Term of patent 7 years

(Cl. D85—2)

To all whom it may concern:

Be it known that I, Alfred R. Albert, a citizen of the United States, and resident of Chicago, in the county of Cook and State of Illinois, have invented a new, original, and ornamental Design for an Ash Tray, of which the following is a specification, reference being had to the accompanying drawing, forming a part thereof:

Fig. 1 is a top plan view of an ash tray, showing my new design.

Fig. 2 is side elevational view of the same.

Fig. 3 is a sectional view through the same taken along the line 3—3 of Fig. 1 and in the direction indicated.

I claim:

The ornamental design for an ash tray, substantially as shown.

ALFRED R. ALBERT.
